BUILDING FACING

John Clarence Udd, Montreal, Quebec, Canada

Application May 8, 1947, Serial No. 746,813

5 Claims.

(Cl. 189—86)

1

The invention relates to improvements in building facing, as described in the present specification and illustrated in the accompanying drawings that form a part of the same.

The invention consists essentially of the novel features of construction as pointed out broadly and specifically in the claims for novelty following a description containing an explanation in detail of an acceptable form of the invention.

The objects of the invention are to devise building facing which may be applied over walls such as concrete, stone, brick and with slight modifications may be secured to any other type of wall; to construct building facing which may be easily assembled together as the same is applied over walls at the building site; to enhance the appearance of plain inexpensive walls with a decorative facing; to furnish metal building facing which may be of aluminum, stainless steel, bronze, brass, plated metals or the like; to facilitate the cleaning of metal building facing in which all fastening means are concealed; to make building facing which may be manufactured in standard units of predetermined sizes and shapes; and generally to provide building facing which will be attractive, durable, inexpensive to manufacture and easy to assemble at the building site.

In the drawings:

Figure 1 is a fragmentary side elevation showing units of the building facing assembled together.

Figure 2 is a sectional plan view as taken on the line 2—2 in Figure 1.

Figure 3 is a fragmentary vertical section as taken on the line 3—3 in Figure 2.

Like numerals of reference indicate corresponding parts in the various figures.

Referring to the drawings, the building facing consists of units or panels as indicated by the numeral 10, and which may be made of any suitable metal or other material. These panels may be various shapes and sizes and are adapted to interlock with one another. In this instance the panel 10 is of an arcuate shape curving inward towards the centre thereof. The outer edges 11 and 12 at each side of the arcuate shaped panel 10 taper inward almost at right angles to the adjacent portion of the latter. The panel 10 has the supporting flange 13 on one side thereof which extends inward towards the wall 14 of the building. The inner edge of the supporting flange 13 terminates in the shape of a T-formation 15 which extends vertically with respect to the same. The rib or bead formations 16 and 17

2

form an integral part of the flange 13 and extend vertically on each side thereof a predetermined distance from the T-formation 15.

The T-formation 15 and the rib formations 16 and 17 of the supporting flange 13 extend parallel with respect to one another and the upper and lower portions are adapted to be engaged by horizontal T-shaped members 18. In this respect the upper and lower portions of the supporting flange 13 located between the T-formation 15 and the rib formations 16 and 17 are cut away or cut-out sufficiently to accommodate the cross-bar of the T-shaped members 18. The outer flange of the T-formation 15 of the supporting flange 13 is secured at the upper and lower ends thereof to the cross-bar of the T-shaped members 18 by means of the screws 19.

The body of the T-shaped members 18 has a plurality of anchor plates 20 welded to the edge 20 thereof and the same are embedded in the concrete wall 14.

The side edge of the panel 10 which has the supporting flange 13 extending inward therefrom has the groove 21 extending vertically throughout the length of same; while the opposite edge or free end of this panel has the tongue 22 extending vertically throughout the length thereof.

In assembling the panels 10 in position on the wall 14 the same are secured in position on the T-shaped member 18 and the tongue 22 of one panel is engaged in the groove 21 of the adjacent panel. The panels 10 are placed side by side and one above the other so as to cover any size of wall, and the band 23 is suitably secured to the same to cover all horizontal joints.

While the panels 10 are adapted to cover straight wall surfaces, it will be seen that with slight modification the same may be adapted to cover corners and also may be arranged to form facing around openings in the wall without departing from the spirit of the invention.

What I claim is:

1. In building facing, a plurality of individual arcuately shaped panels placed side by side and interlocking with one another, a supporting flange extending inward from one end of each of said panels, a T-formation formed in each of said supporting flanges and being integral therewith, rib formations integral with each of said supporting flanges and being suitably spaced apart from said T-formation and extending parallel with respect thereto, the upper and lower portions of each of said supporting flanges being cut out between said T-formation and said rib

formations of same, horizontal T-shaped members accommodated in the cut out portions in each of said supporting flanges, screws securing the outer flanges of said horizontal T-shaped members to one of said rib formations on each of said supporting flanges.

2. In building facing, a plurality of individual arcuately shaped panels placed side by side and interlocking with one another, a supporting flange extending inward from one end of each of said panels, a T-formation formed in each of said supporting flanges and being integral therewith, rib formations integral with each of said supporting flanges and being suitably spaced apart from said T-formation and extending parallel with respect thereto, the upper and lower portions of each of said supporting flanges being cut out between said T-formation and said rib formations of same, horizontal T-shaped members accommodated in the cut out portions in each of said supporting flanges, screws securing the outer flanges of said horizontal T-shaped members to one of said rib formations on each of said supporting flanges, a plurality of anchor plates welded to the inner edge of the body of said horizontal T-shaped members, said anchor plates being embedded in a concrete wall.

3. In building facing, a plurality of metal panels, each of said panels being of an arcuate shape curving inward towards the centre thereof, the outer edges of each side of said panels tapering inward at almost right angles to the face thereof, each of said panels have a groove in one end thereof and a tongue on the opposite end of same, a supporting flange integral with each of said panels and extending inward from one edge thereof, the inner edge of said supporting flange terminating in the shape of a T-formation, said supporting flange having bead formations extending vertically on each side thereof a predetermined distance from the T-formation of same, horizontal T-shaped members, anchor plates secured to said horizontal T-shaped members and embedded in a wall, the T-formation and bead formations on said supporting flange engaging said horizontal T-shaped members for substantially supporting said panels, said panels being placed side by side and the tongue of one panel engaging the groove in the adjacent panel, said panels being placed one above the other, and a band coinciding with the contour of said panels and concealing all horizontal joints therebetween.

4. In building facing, a plurality of metal panels, each of said panels being of an arcuate shape curving inwards towards the centre thereof, the outer edges at each side of said panels tapering inward to join one another in a V-shaped manner, each of said panels having a groove in one end thereof and a tongue on the opposite end of same, a supporting flange integral with one end of each of said panels and extending inward therefrom, the inner edge of said

supporting flange terminating in the shape of a T-formation, said supporting flange having bead formations extending vertically on each side thereof a predetermined distance from the T-formation of same, the upper and lower portions of said supporting flanges located between the T-formation and bead formations of same being cut-out to provide clearance spaces, horizontal T-shaped members partially embedded in a wall, the cross-bar of said T-shaped members being accommodated in the clearance spaces in said supporting flange and engaging the T-formation and bead formations of the former, said panels being placed side by side and one above the other, the tongue on the side of one of said panels engaging the groove in the adjacent said panel and the angularly disposed edges of said panels forming a finished joint, and bands following the contour of said panels thus concealing horizontal joints between the same.

5. In building facing, a plurality of panels, the body of each of said panels being arcuately shaped, the outer edges at each side of said panels being angularly disposed with respect to the body portion of same adjacent thereto, each of said panels having a groove in one end thereof and a tongue on the opposite end of same, a supporting flange integral with each of said panels and extending inward from one edge thereof, the inner edge of said supporting flange terminating in the shape of a T-formation, said supporting flange having bead formations extending vertically on each side thereof a predetermined distance from the T-formation of same, horizontal T-shaped members, anchor plates welded to said horizontal T-shaped members, said anchor plates being embedded in a concrete wall, the T-formation and bead formations on said supporting flange engaging said horizontal T-shaped members for substantially supporting said panels, said panels being placed side by side and the tongue of one of said panels engaging the groove in the adjacent said panel, said panels being secured in position on a wall one above the other, and bands following the contour of said panels and being fixedly secured to the upper and lower edges thereof thus concealing the horizontal joints therebetween.

JOHN CLARENCE UDD.
